COLON FLUSHING APPARATUS

Julien A. Bried, Berkeley, Calif.

Application July 27, 1954, Serial No. 446,065

8 Claims. (Cl. 128—227)

This application is a continuation in part of my co-pending application originally entitled "Colon Flushing Apparatus" under Serial No. 256,525, Nov. 15, 1951, but which title was changed by the patent examiner so that a patent will issue in that case under the changed title "Colon Flushing Nozzle with Dissolvable Tip" with claims limited to the nozzle and dissolvable tip, and the present case is drawn to cover the gravity discharge control shown in my prior application, together with an improvement on said control.

The invention relates to apparatus for irrigating or flushing the human colon, and has for its principal object the provision of means to supplant the use of an enema bed pan for bed ridden persons incapable of having proper natural movements, or of substantially aiding in the elimination of fecal matter from their bowels even when given an enema, as frequently the case with persons that are paralyzed or partially so.

Other objects and advantages of the invention will appear in the following description and accompanying drawings.

In the drawings:

Fig. 1 is a side elevation of the improved colon flushing apparatus and with part of the rectal nozzle and its tip shown in section. The arrangement of the apparatus in this figure is as if being applied to a patient lying on his side at the edge of a bed. Preferably a hospital bed to get more elevation to the drainage bucket on the floor.

Fig. 2 is a cross section of the controlling valve of Fig. 1 as seen from the line 2—2 of Fig. 1.

Fig. 3 is a rear end view of the valve as seen from the line 3—3 of Fig. 2.

Fig. 4 is an elevation of the apparatus like that of Fig. 1 but in reduced scale and showing a modification in the drainage control and a foot operated control of the discharge valve.

Fig. 5 is a plan view of the foot pedal of Fig. 4 taken from the line 5—5 thereof.

Fig. 6 is a cross section of a modified arrangement of the passages or ports in the nozzle control valve.

Before describing the drawings in detail it will be helpful to state that the apparatus relates more to simple home-use devices for the purpose above set out so as to do away entirely with the administering of ordinary enemas with the use of bed pans, yet easily secure a much more complete removal of the feces than is possible even with other flushing apparatuses in cases where the patient cannot aid in expelling it or where a portion of it will not pass through any conventional rectal nozzle connected to a discharge hose, as the opening in the tip of such nozzles are necessarily much smaller than the nozzle tube as the end of the tube must be tapered down to a rounding point for insertion, and if the hole at the end were large there would be no point left, and any side openings provided are of little use as they are blocked by the walls of the colon.

The present invention overcomes the above objections.

2

by providing an extra large nozzle tube and bore extending straight through it without restriction, but capped on the outer end with a removable roundingly pointed pilot tip which is quickly disintegrated or dissolved after entry 5 into the colon upon passing the irrigation water into the colon to disperse the disintegrable tip and soften the feces, to thus expose the free fully open end of the nozzle tubes large bore to freely receive the fecal matter and pass it through the bore to, at least an equally large bore 10 rubber hose or other discharge tube leading ever downward to a floor bucket, the withdrawal of the matter being considerably aided by a suctional pull suddenly applied by dropping a standing column of water first established in the downwardly extending discharge tube 15 to the bucket.

The present apparatus permits the above operation to be carried out by a single practical nurse in a few minutes with the patient lying on one side close to the edge of the bed (preferably a hospital bed to gain elevation), so that the discharge hose will lead downward.

With the above explanation of the purpose of the apparatus the details of construction will be more clearly understood.

In the drawings Fig. 1 the rectal nozzle is indicated at 25 1, its separate disintegrable entering or pilot point or tip 1', its control valve 3, discharge tube or hose 4, water supply tube 5, floor bucket 6.

The above constitute the main features of the apparatus. The rectal nozzle is preferably made of hard 30 rubber or a hard plastic, though it may be of metal, and the valve also. The valve is preferably a three-way taper plug type valve which may be formed on or secured to the rear end of the rectal nozzle so that a nurse 35 can manipulate the valve while at the same time hold the nozzle from being accidentally pulled out of the rectum.

Hoses 4 and 5 are preferably of rubber or plastic, and hose 4 is preferably translucent or transparent so that the discharging matter may be easily observed. The 40 hoses are attached to the valve over nipples 7 and 8, and the bores or passages in hose 4 and in the valve being of a size to preserve at least the full uninterrupted diameter of the bore 9 of the nozzle, but the water inlet hose 5 and its attaching nipple 8 may be much smaller 45 as indicated.

Hose 5 leads down from any elevated container or low pressure of warm water, soapy or medicated as desired, with which to flush or irrigate the patient's colon. Discharge hose 4 is shown, in Fig. 1, to be detachably 50 held in place at the upper edge of a slop bucket 6 as by a spring clip 10 so that its lower end will remain above any liquid level in the pail, and preferably attached to the clip adjacent the lower end of the hose 4 is a hose-pinching clamp 11 or any other type of quick opening 55 shut-off valve, kept closed until it is desired to siphon off the contents of the colon, and which is done (assuming that the desired quantity of water had been introduced into the colon, and left there for a few minutes, and that hose 4 was full of water), by first turning valve 60 3 to the position shown in Fig. 1 to connect its passage 16 with the nozzle bore and hose 4, then at once quickly opening hose clamp valve 11 to suddenly drop the liquid column of hose 4 into the bucket 6 and thereby create a suction to also draw out of the colon the loosened 65 liquid content.

With the valve 3 in this discharge position its indicator 17 will point at a small numeral 5 on its rim, and after the discharge the valve indicator may be turned to position numeral 1 to permit water from hose 5 to wash out the discharge hose 4 while the lower valve 11 is open, and upon closing 11 fill up hose 4 again, then by turning

valve 3 to position 3 it will permit the water to again flow into the patient for repetition of the treatment. The other or between positions of the valve 3 are all closed positions. A hose-pinching valve may conveniently be placed on fresh water hose 5, as at a point 12 so that it may be disconnected from the valve 3 when finished and the apparatus removed for washing up.

The valve plug 3 fits within a housing shell 13 and the plug is turned by means of a thumb and finger operated handle 15 at the large end of the plug and which handle is curved as shown in Fig. 1 to indicate the extension of the valve passage 16 through the plug so that a glance at it will show the nurse how the valve is set at any time. However, an audible indicator or "click" takes place at every one of its six positions marked around the edge of the housing shell by the small numerals 1 to 6 as indicated by the pointer 17 on the plug. The "click" is produced by the ends 18 of a small leaf spring which snap into slight depressions around the small end of the shell, each formed with an abrupt edge 19, or any other suitable detent. This spring also resiliently holds the tapered plug 3 in its seat as it fits over a squared part 20 of a shank 21 extending from the small end of the plug and is held in place as by a thumb nut 22. Thus, if the edges 19 are abrupt enough the plug may be turned one way only (to the right or clockwise) and cannot be reversed. This makes it impossible for soiled liquid from the discharge getting into the fresh water, as the valve must necessarily be turned through the valve-plug washing position 1 before any more fresh water can be introduced into the rectum nozzle.

It should be noted that the forward end of the rectal nozzle is well rounded so that after the pilot has dissolved and the tube is withdrawn it will not injure the lining of the colon. The disintegrable quality of the pilot tip may be achieved in various ways as set out fully in my copending patent application referred to, now Patent No. 2,691,373 dated October 12, 1954. In using the pilot tip, it is first placed in the end of the nozzle, being sure the end of the nozzle is not wet, the tip is then lubricated as with "Vaseline," also the rectum, and the nozzle inserted with one movement, without any withdrawing action to dislodge the tip. The amount of irrigating water admitted each time would be like any enema, and the doctors advice, and would be gaged from an elevated supply gaged tank or glass container graduated for the nurse to plainly see, as well understood, and not shown. Any air in the hoses may be shaken out with inlet hose open.

In the modified form of the discharge control shown in Figs. 4, 5, and 6 the descending discharge hose is designated 4' and is preferably controlled by a foot operated valve 30 just above the receiving floor bucket 6' so that the nurse will not have to stoop to operate it as she would with the valve 11 of Fig. 1, but can keep her mind always with the conditions above bed with both hands free to hold the nozzle from slipping out etc. and operate the water control.

In this modification the upper valve 3 of Fig. 1 may be used, or the one shown in cross section in Fig. 6 which provides for an additional function, i. e. it may be turned to direct a stream of fresh water from hose 5 into the outflowing discharge stream while the patient is being evacuated so as to function somewhat as a mild hydraulic ejector, to thus gain more and longer siphonic action. This effect may also be obtained by the proper manipulation of two hand operated common hose-pinching valves 31 and 32 respectively on rubber tubes 5' and 4' as indicated in Fig. 4 where hose 4' which extends from the rear end of the rectal nozzle 1 down to the bucket 6' has a special T fitting 33 interposed in it at a point a short distance below the nozzle, and which fitting has a side inlet branch 34 to receive the fresh water hose 5' and which branch enters the T at a downwardly curving slant so that when valve 31 is opened the inflowing water will

tend to squirt a stream down the discharge tube 4', so that if the bucket valve were open and a bowel discharge taking place this additional stream entering at the angle as stated will both increase the suctional discharge and also prolong it.

To run fresh water into the patient only, valve 32 is closed, and valve 31 is opened or, if the bucket valve is closed and the descending tube 4' is full of clean water, more water incoming from valve 31 will simply back up into the patient.

In place of this special T 33, the modified valve plug 35 may be used, and which, when turned with main port 16' in colon discharge position as shown in the drawing Fig. 6 will also bring a smaller port 36 into communication with the fresh water inlet of hose 5' and direct a stream therefrom at an angle down toward the outlet hose to help urge the discharge to the bucket if foot valve is open. From the form of the valve port 16' it will be seen that if from position B shown, the plug be turned 20 a trifle to the right to G it will shut off the fresh water inlet while still preserving a full open discharge passageway from the colon nozzle to the lower portion of the discharge hose 4'. The plug may be turned to either A, C, or E to shut off all passages, or to position 25 F for admitting fresh water to the colon only. Also, if in B position and foot valve is closed, and nozzle not yet in patient, fresh water will fill up system to the open end of the nozzle held upwardly while air escapes from nozzle, then turned to C to shut off water, then apply 30 the soluble tip on nozzle and insert in the patient, then turn to D or F to admit water to patient, then shut valve again to soak in patient as desired.

To gain a longer time discharge suction, descending hose 4' may be of somewhat enlarged cross section 35 throughout its central portion as indicated at 4', but of course must be strong enough to withstand collapse.

The foot control bucket valve may take various forms and is generally designated 30 in Fig. 4, and comprises a floor or base plate 38 with a standing bar or pipe 39 secured at its lower end to the plate, and adjacent to which bar the bucket 6' is stood on the plate. At the upper end of the bar is a rigid bracket 40 overhanging the bucket and formed to frictionally embrace the lower end of the hose 4' as shown. Just under this bracket is a rocker 41 straddling the bar and pivoted thereto as at 45 41' and carrying a hose pinching roller 42 at its end over the bucket, and at its other end pivotally connected to a wire 43 which extends downwardly and is pivotally connected at its lower end as at 44 to a pedal 45 in turn pivoted for up and down motion at its opposite end at 46 50 to the floor plate. The pedal is urged upward as by a spring 47 to normally hold the hose pinching roller 42 retracted from the discharge hose, as shown in the drawing. The arrangement being such so that when the pedal is pushed down by the foot of a nurse it will rock the 55 roller to the left and pinch the hose 4' over against the overhanging lip 40' of the bracket and close the hose, and when in this position the forward end of the pedal will lock down in a notch 48 in the lower part of the bar 39 to hold the discharge hose closed until released by the 60 foot of the nurse being moved to the right to strike the upwardly turned end 45' of the pedal to thus pull the pedal out of engagement with the notch 48 and at which the discharge hose will instantly be opened to drop the standing leg of water in the hose into the bucket and to 65 thereby create the suctional pull on the colon contents as described, of course the valve 35 being at the same time turned to position B.

To permit the pedal to be thus moved slightly to the right to release it from the locking notch, the pivotal 70 mounting of the pedal includes an upwardly and rearwardly slanted slot 49 in a pair of lugs 50 on the floor plate and in which slot the pivot pin 51 of the pedal rides. With this arrangement, an additional advantage is that the floor bucket is always free to be taken away for 75 emptying without disturbing the hose or floor stand.

Having thus described my improved control system in colonic flushing, together with variations in the apparatus for carrying out the system, what I claim is:

1. In a colonic flushing apparatus having a rectal nozzle connected to a water inlet and valve means controlling water flow to the nozzle, a downwardly extending discharge hose leading from said nozzle to a lower slop receiver, a closure at the lower end of said hose for maintaining a standing column of water therein, and which upon sudden opening will drop said column of water into said receiver and create a mild suction on the colon discharge, and foot operated means for operating said closure to preserve a nurse's hands free for manipulating the nozzle and water supply.

2. In a colonic flushing apparatus having a rectal nozzle connected to a water inlet and valve means controlling water flow to the nozzle, a downwardly extending discharge hose leading from said nozzle to a lower slop receiver, a closure at the lower end of said hose for maintaining a standing column of water therein, and which upon sudden opening will drop said column of water into said receiver and create a mild suction on the colon discharge, and foot operated means for operating said closure to both open and closed position to preserve a nurse's hands free for manipulating the nozzle and water supply.

3. In a colonic flushing apparatus, control means for the lower end of a discharge hose leading downward from a patient comprising a floor stand provided with a rigid upright member adjacent which a slop pail is adapted to be stood, means at the upper end of said member arranged to hold the lower end of said hose in overhanging relation to said pail, valve means for closing and opening the hose adjacent its lower end, and foot operated means on said floor stand for operating said valve means arranged to hold it in either position when the foot is removed.

4. In a colonic flushing apparatus of the character described, the combination of a tubular rectal nozzle having a passage therethrough, a finger operated rotary valve means adjacent to the rear end of the nozzle for controlling the flow of liquid to and from said nozzle constructed and arranged to successively carry out the following steps upon a one-way rotation: starting from a position shutting off a water supply port, open the water supply port to the nozzle passage, shut off the water supply port and shut the nozzle passage, open the nozzle passage to a waste discharge port, connect the water

supply port with the waste discharge port only, close the water supply port as at the start for repetition of the steps set out upon the next same directional rotation of the valve means.

5. In the combination as set out in claim 4 means limiting said valve means to said one-way only of turning to require operation of said steps in the order stated only.

6. In a colonic flushing apparatus for a patient in recumbent position on one side and elevated as lying on a hospital bed, the combination of a rectal nozzle and a discharge tube extending downwardly from the nozzle (when in place) to a lower receiving bucket substantially on the floor, valve means for closing the lower end of said tube adjacent its outlet arranged to maintain an upwardly extending unobstructed column of water in said tube substantially to the patient, a branch tube joining said discharge tube near its upper end valved for the admission of water to said discharge tube and for irrigating the patient through said nozzle when the discharge tube is closed off at its lower end by said valve means, all whereby when said valve means is suddenly opened said column of water will fall into said bucket and create a suction to pull liquid contents of the colon with it.

7. In an apparatus as set out in claim 6 the passageway of said branch tube where it joins the discharge tube being smaller than the passageway of the discharge tube at that point and directed downwardly thereinto in a manner to function as an hydraulic ejector jet on the falling discharge when the irrigating water is turned on during the falling of such discharge when said valve means at the lower end of the discharge tube is opened.

8. In an apparatus as set out in claim 6, said discharge tube being at least in part of an inside diameter considerably greater than the effective diameter of the nozzle bore to prolong the suctional discharge.
